UNITED STATES PATENT OFFICE.

CHARLES S. BOARDMAN, OF BUFFALO, NEW YORK, ASSIGNOR TO LACKAWANNA STEEL COMPANY, OF LACKAWANNA, NEW YORK, A CORPORATION OF NEW YORK.

CONSTRUCTION OF CAISSENS, COFFERDAMS, AND THE LIKE.

1,398,221.

Specification of Letters Patent. Patented Nov. 29, 1921.

Application filed December 18, 1919. Serial No. 345,726.

To all whom it may concern:

Be it known that I, CHARLES S. BOARDMAN, a citizen of the United States, residing at Buffalo, in the county of Erie and State of New York, have invented new and useful Improvements in the Construction of Caissons, Cofferdams, and the like, of which the following is a specification.

This invention relates to an improved method of constructing and installing metal caissons for use in subaqueous work in the construction of piers, foundations, and the like. The several features of my present invention are particularly applicable for the construction of caissons formed of interlocking metal sheet piling and consists in an improved construction and arrangement thereof which allows of the installation being made more conveniently, accurately and economically than heretofore. The improvements of my present invention are particularly advantageous in the construction of bridge pier or other foundations through water and in material such as fine sand or silt.

As is well understood, in the building of bridge pier foundations open caissons of interlocking steel piling are extensively used and have commanded recognition from an engineering standpoint particularly as to cost of installation for it has been found that great economy has accompanied the use thereof. There are, however, many locations particularly in sub-aqueous work where it has heretofore been required that the caissons be assembled *in situ* particularly where the caisson is to be driven through sand or silt to bed rock. This method of construction involves considerable expense particularly in bridge pier construction and where a substantial amount of interior bracing is found necessary and when it is further required that additional bracing be installed as the silt or sand is removed from within the caisson as the work progresses.

The improved construction and arrangement of the present invention is designed to permit of the assembling of the caisson with its co-acting interior bracing in any convenient location with economy from which it may be lifted as a unit and set into the position to be driven and further adapted to then permit of the individual piling sections being separately and economically

driven to the depth required. As a result of this arrangement not only may the assembling of the caisson be performed under the most economical conditions but, in addition, when placed in position for driving, the latter operation may be performed by the employment of the simple pile driver thus preserving the economy resulting therefrom peculiar to the use of the interlocking pile sections.

Important features of my improved arrangement comprise a separable reinforcing cage or bracing form associated with the piling wall of interlocking sections so as to provide internal bracing therefor and this cage is further adapted to have the piling sections temporarily or releasably attached thereto. By this arrangement provision is made for temporarily securing the inclosing wall of piling elements or sections to the reinforcing cage whereby they may be fully assembled adjacent to the final location. This permits the entire structure, fully assembled, to be handled as a unit and conveniently lifted into place for driving. As further contemplated, when in position, the piling sections are released from connection with the reinforcing cage to allow of their being separately driven to final location.

The construction of my improved separable reinforcing cage, as a connected unit, also permits of progressively lowering the bracing or settling of the cage as the piling is driven and the sand or silt is removed from the bottom of the caisson structure. In its preferred form I desirably construct the separable reinforcing cage as a connected unit formed of a series of annular bracing members suitably connected by vertical spacing members and having a central and unobstructed opening therethrough providing a spacious open interior which will permit of removing the material from the bottom of the caisson by means of a suitable excavating bucket. As a result thereof, in typical installations the caisson as aforesaid may be fully assembled above water, placed in position and the piling driven fully or partially, as the circumstances permit, and the bracing lowered progressively as the material is removed and the caisson sunk into final position. The interior of the caisson may be then unwatered as the conditions require or the foundation may be completed in

many instances without unwatering by merely placing the concrete in the caisson so installed; in the latter case the caisson becoming part of the pier structure. It will 5 thus be understood that in many instances the installation may be successfully performed by operation entirely above water level thereby eliminating many of the troublesome features incident to subaqueous 10 work and effecting substantial economy in the cost of installation.

The described and other features and advantages of my invention will be understood by reference to the accompanying drawings 15 wherein like reference numerals are applied to the corresponding parts in the several views. Referring to the drawings:—

Figure 1 is a vertical cross sectional view of a caisson constructed in accordance with 20 my invention.

Fig. 2 is a partial plan view thereof and

Fig. 3 is a diagrammatic view showing a typical installation.

In the approved embodiment of the features of my present invention as illustrated 25 in the drawings herein, 1 indicates the sheet piling sections of any suitable form of which the required number are assembled with their interlocking elements in engagement 30 to form a caisson or inclosing wall of the desired size and shape. In accordance with my present improvements the piling sections are assembled to inclose a reinforcing cage or bracing form as here shown composed of 35 a vertically arranged series of annular reinforcing members or rings 3 formed of angle bars or channels and connected in spaced relation by means of vertically arranged tubular posts 5 engaging the horizontal 40 flanges of the annular members and having connecting or tie-rods 6 passed therethrough and also through the horizontal flanges 4 of the annular members and having threaded upon their projecting extremities suitable 45 securing nuts 7. A suitable number of these connecting members 5 and 6 are disposed circumferentially of the respective members 3 connecting each of said members with the corresponding member thereabove or there- 50 under whereby the respective annular reinforcing members 3 are rigidly connected in vertical alinement in their proper spaced relation to afford the required bracing for the caisson when in final position.

55 The whole bracing or reinforcing structure is accordingly connected up as a rigid unit which permits of its being transported as such. The interlocked sections of sheet piling as illustrated are of increased length 60 relative to the height of the bracing structure to provide a clearance for driving which may correspond approximately to the distance between the reinforcing members 3. It is further provided that the inclosing wall 65 of interlocked piling sections when assembled

therewith shall be temporarily or releasably attached to the reinforcing unit so formed whereby the entire caisson structure may be assembled fully above water level and thereafter transported or lifted as a unit into 70 position for installation.

For the latter purpose, that is, for temporarily securing the piling wall to the reinforcing structure, simple means may be employed; for instance as here shown, each 75 of the piling sections is provided with an aperture through its web portion adjacent to its upper edge adapted to receive therein a securing bolt 9 carried by the uppermost reinforcing ring or bracing member 3. As 80 indicated this uppermost bracing ring may desirably be composed of channel bars 10, 10 secured in spaced relation with their flangeless sides or flat surfaces opposed. The channel bars 10, 10 are suitably spaced by 85 means of spacing washers 11 surrounding the rod 6 to suitably space the channels to closely receive therebetween the attaching bolts 9 for the respective piling sections. This arrangement permits of the shanks of 90 the bolts 9 being adjusted circumferentially to obtain proper registration with the apertures of the individual piling sections. Suitable washers 12 are desirably interposed between the inner peripheral surface of the 95 channels 10, 10 and the bolt heads 13 and as will be understood the bolts are threaded on their outer projecting extremities to receive the securing nuts 14 threaded thereon. The arrangement as shown thus provides for 100 detachably securing each of the piling sections at its top to the reinforcing cage or structure whereby as will be obvious the complete caisson may be lifted by means of a cable or cables attached thereto, for instance to the topmost bracing ring 3.

The use of my improved construction described permits of the installing of the caisson in the improved method as follows:—

The initial assembling of the caisson as 110 will be readily understood may be performed at a convenient location and either with the structure in a horizontal or vertical position as may be more convenient. Having detachably secured the inclosing 115 wall of interlocked piling sections to the bracing form by means of the bolts described, a suitable crane may be employed to lift the structure by attaching the cables thereof to the top ring or bracing member 120 and the entire assembled structure may thus be transferred and positioned in the desired final location. When thus positioned the securing nuts 14 may be conveniently removed by reason of their exposed location at the 125 top of caisson and the bolts may be withdrawn or driven out thereby releasing the piling sections from connection with the interior bracing. This will permit the bracing form to lower into position of rest upon 130

the soil beneath and will correspondingly lower the bracing form with reference to the upper ends of the piling sections; the bracing cage being as illustrated of such 5 relative height with reference to the length of the piling sections to then permit of the piling extending thereabove a distance sufficient to permit of the piling sections being driven. A driving clearance is thus afforded above the uppermost of the bracing rings 10 allowing for the use of a pile driver to act upon the individual piling sections to successively drive said sections to the extent permitted by said clearance which may in some installations be sufficient for driving 15 of the piling to bed rock or final position. In this case the sand or silt at the bottom of the inclosure may be removed by a suitable bucket operating within the central 20 and unobstructed space inclosed by the bracing rings or the sand may be ejected through pipes with water or air pressures. Should, however, the conditions require that the piling wall and caisson structure be driven a 25 substantial distance it will be understood that it is first lowered to a position of rest upon the sub-surface or river bottom, the piling sections released as aforesaid and driven successively to the extent permitted. 30 The sand or silt at the bottom of the caisson is then removed permitting the bracing cage to drop or be lowered again to the bottom of the cylinder of piling again allowing the driving of the individual sections to be repeated and the structure to be 35 progressively lowered into final position.

Thus my improved construction permits of the structure as a whole being progressively lowered into final position by alternately driving the individual piling sections until their tops are at the elevation of the top ring of the cage and excavating so that the cage of bracing can be settled or lowered to a successive position at the bottom 45 of the wall, the operation being carried out entirely from above water-level. Thus the repetition of driving and excavating with the lowering of the cage allows the structure gradually to be driven or settled to its 50 final position on bed rock or at a depth required for the necessary bearing value of the foundation.

By the use of the steel piling sections of the type shown each can be driven independently and therefore easily and economically and moreover each of said sections may be driven independently to bed rock so that the bottom of the caisson conforms thereto thereby adding to the strength and water-tightness. The advantages of ease and economy of installation are obvious and substantial for the reason that all work is performed from above water level. In this connection it will be understood that the 65 structure is driven to its final position be-

fore unwatering should it be thereafter desired to carry on sub-aqueous work. However, in many installations the caisson may not be unwatered and the foundation completed by merely placing concrete in the cylinder structure. There is thus produced an improved construction combining the advantages of the completed unit caisson so as to avoid the expense incident to assembling in final position and also the advantages of 70 piling wall construction with accompanying economy in driving, thereby eliminating the expense and difficulties of installation heretofore peculiar to assembled or unitary caisson installations. 80

While I have described a desirable embodiment of the many features of my invention it will be understood that many modifications may be made therein without departing from the scope thereof as defined in the appended claims. It is therefore intended that all matter herein shall be interpreted as illustrative and not in a limiting sense.

Having described my invention, I claim:— 90

1. A structure of the character described comprising an inclosing wall of steel sheet piling sections and bracing members therefor and means to detachably secure the piling sections to the bracing members to permit of the assembling and handling thereof as a unitary structure and to thereafter permit of driving the piling sections independently, substantially as described. 95

2. A structure of the character described comprising an inclosing wall of interlocking steel sheet piling sections and a bracing form therefor and means to detachably secure the piling sections to the bracing form to permit of initially handling the bracing form and 100 piling sections as a unitary structure and to thereafter permit of driving the piling sections independently of the bracing form, 105 substantially as described.

3. A caisson structure comprising an inclosing wall of interlocking steel sheet piling sections and a bracing form therefor, said bracing form consisting of reinforcing members arranged in spaced relation and connecting members therebetween connecting said reinforcing members as a unitary structure and means to detachably secure the piling sections to the bracing forms thereby to permit of handling the piling sections and bracing form as a unitary structure and to 110 thereafter permit of driving the piling sections independently of the bracing form, 115 substantially as described.

4. A caisson structure comprising an inclosing wall of interlocking steel sheet piling sections and a bracing form therefor, said bracing form consisting of reinforcing members positioned in spaced relation and connecting members therebetween secured to the respective reinforcing members and 120 125 130

said bracing form having an interior opening therethrough and means for detachably connecting each of the piling sections to the bracing form to allow for initially handling 5 the caisson as a unitary structure and thereafter to permit of driving the piling sections independently, substantially as described.

5. A caisson structure comprising an in- 10 closing wall of interlocking piling sections and interior bracing therefor composed of suitably spaced reinforcing members having connecting members therebetween for connecting said reinforcing members as a struc- 15 tural unit and means for releasably connecting each of the piling sections to the bracing unit adjacent the top thereof thereby to permit of assembling the piling and bracing as a unitary structure and to there- 20 after permit of driving the piling sections independently, said releasable connecting means comprising securing bolts fitted to suitable apertures respectively in the brac- 25 ing and piling sections, substantially as described.

6. A caisson structure comprising an in- 30 closing wall of interlocking piling sections and interior bracing therefor composed of suitably spaced reinforcing members hav- 35 ing connecting members therebetween for connecting said reinforcing members as a structural unit and means for releasably connecting each of the piling sections to the bracing unit adjacent the top thereof thereby to permit of assembling the piling and bracing as a unitary structure and to there- 40 after permit of driving the piling sections independently, said releasable con-

necting means comprising securing bolts fitted to suitable apertures respectively in the 40 bracing and piling sections and said bracing being formed with a centrally enlarged opening therethrough, substantially as described.

7. A structure of the character described comprising an inclosing wall of interlocking sheet piling sections and an interior 45 bracing form therefor and means adapted to initially engage each of said piling sections with the bracing form to permit of their being lifted as a unit and thereafter 50 to permit of driving the piling sections independently, substantially as described.

8. A caisson structure comprising an in- 55 closing wall of interlocking steel sheet piling and interior bracing therefor, said bracing consisting of a series of reinforcing members suitably spaced, connecting members therebetween consisting of tubular spacing members interposed between the reinforcing members and tie rods passed therethrough 60 and through apertures in the reinforcing members and the uppermost of said reinforcing members having an annular slot there- 65 through, securing bolts fitted within the slot with their shanks outwardly directed to register with apertures in each of the piling sections to establish a detachable connection therewith initially to permit of the piling sections and bracing form to be lifted as a unitary structure and securing nuts 70 threaded to the projecting ends of the bolts, substantially as described.

In testimony whereof I have signed my name to this specification.

CHARLES S. BOARDMAN.
